Primary Examiner — Cathron C Brooks*Assistant Examiner* — Ian F Whitmore(74) *Attorney, Agent, or Firm* — Muncy, Geissler, Olds & Lowe, P.C.(57) **CLAIM**

The ornamental design for a display screen with graphical user interface, as shown and described.

DESCRIPTION

FIG. 1 is a front view of the first image in a sequence for a display screen with graphical user interface showing a first embodiment of the new design;

FIG. 2 is a front view of the second image thereof;

FIG. 3 is a front view of the first image in a sequence for a display screen with graphical user interface showing a second embodiment of the new design; and,

FIG. 4 is a front view of the second image thereof.

The dot-dash perimeter illustrates a display screen and forms no part of the claimed design. The remaining broken lines illustrate portions of a graphical user interface and form no part of the claimed design.

The appearance of the transitional image sequentially transitions between the images shown in FIGS. 1–2 in the first embodiment, and FIGS. 3–4 in the second embodiment. The process or period in which one image transitions to another forms no part of the claimed design.
